UNITED STATES PATENT OFFICE.

WILLIAM GASKELL AND THOMAS VALE, OF FAYETTE CITY,
PENNSYLVANIA.

HAT-PIN.

No. 857,614.

Specification of Letters Patent.

Patented June 25, 1907.

Application filed October 16, 1906. Serial No. 339,191.

To all whom it may concern:

Be it known that we, WILLIAM GASKELL and THOMAS VALE, citizens of the United States of America, residing at Fayette City, in the county of Fayette and State of Pennsylvania, have invented certain new and useful Improvements in Hat-Pins, of which the following is a specification, reference being had therein to the accompanying drawing.

10 This invention relates to certain new and useful improvements in hat pins and the invention has for its object the provision of novel means in connection with a pin, for retaining the same in a hat.

15 Another object of this invention is to provide a simple and inexpensive hat pin which can be easily and quickly manipulated without injuring the hat.

With these and other objects in view, the 20 invention consists in the novel construction, combination and arrangement of parts to be hereinafter more fully described and then specifically pointed out in the appended claims.

25 Referring to the drawing forming part of this specification, like numerals of reference designate corresponding parts throughout the several views, in which:

Figure 1 is a plan of our improved pin, 30 Fig. 2 is an enlarged detail sectional view of the movable member of the pin, Fig. 3 is an enlarged fragmentary sectional view of said member, and Fig. 4 is a detail of one of the push pins of the member.

35 To put our invention into practice, we employ an ordinary hat pin 1 having an ornamental head 2. The pin 1 adjacent to the pointed end 3 thereof is provided with a plurality of circumferentially arranged grooves

40 4. A removable member 5 is adapted to slide on the pin 1, and has a bore 6 formed therein in which is threaded a cap 7 having an opening 8 adapted to aline with the opening 9 of the member 5 whereby the pin 1 can

45 pass through said member. Communicating with the bore 6 are two diametrically opposed openings 10 containing spring-held push pins 11, said pins having heads or buttons 12. The inner ends of the pins are

50 loosely connected to levers 14, said levers be-

ing pivotally mounted in the bore 6 as at 15 and formed with inwardly extending ends 16 adapted to engage in one of the grooves 4 of the pin. The levers 14 are normally held in engagement with the pin by the springs 55 forcing pins 11 outwardly, and when it is desired to adjust or remove the member 5 from the pin 1, the push pins 11 are forced inwardly to disengage the inwardly bent ends 16 of the levers from the pin 1. 60

After the hat pin 1 has been passed through a hat, the member 5 is placed upon the end of the pin and moved until it engages the hat, at which time it is locked in the groove 4 nearest to the hat. It will thus be impossible for the hat pin to become lost or disengaged from the hat in which it is placed. 65

We do not care to confine ourselves to the style of pin in connection with which the member is used, and such other changes as 70 are permissible by the appended claims, may be resorted to without departing from the spirit and scope of the invention.

What I claim and desire to secure by Letters Patent, is:—

75 1. A hat pin having a plurality of circumferentially-arranged grooves adjacent the pointed end of the pin, a removable securing member apertured to receive the hat pin and bored in one end, a plug threaded into said bore and centrally apertured to receive the hat pin, a pair of levers pivoted in the bore of said securing member at opposite sides of the hat pin and having their outer ends turned inwardly toward the pin to engage in said circumferentially arranged grooves in the pin, push pins pivotally connected to the inner ends of said levers and extending outwardly through the securing member and having heads on their outer ends, and springs 85 arranged on said push pins between the levers and the heads for normally holding the inturned ends of said levers in engagement with the pin.

2. A hat pin having a fixed head, and having a plurality of grooves adjacent its pointed end, a removable securing member slidable on the pin and having an enlarged bore in one end, the walls of which are free from engagement with the pin, a lever pivoted within the 90

100

bore of said securing member and having its outer end turned inwardly toward the pin to engage the grooves thereof, and a spring pressed push pin pivotally connected to the inner end of said lever and extending outwardly through the securing member, substantially as described.

In testimony whereof we affix our signatures in the presence of two witnesses.

WILLIAM GASKELL.
THOMAS VALE.
